UNITED STATES PATENT OFFICE.

LAWRENCE H. DOLAN, OF ALEXANDRIA, INDIANA, ASSIGNOR OF THREE-FOURTHS TO THOMAS A. NILAN, LOUIS KAUFFFIELD, AND VALENTINE LIBLER, OF SAME PLACE.

DESIGN FOR AN INCANDESCENT-LAMP BULB.

SPECIFICATION forming part of Design No. 26,827, dated March 30, 1897.

Application filed February 11, 1897. Serial No. 623,010. Term of patent 7 years.

To all whom it may concern:

Be it known that I, LAWRENCE H. DOLAN, of Alexandria, in the county of Madison and State of Indiana, have invented and produced 5 a new and original Design for an Incandescent-Lamp Bulb, of which the following is a full, clear, and exact description.

Reference is to be had to the accompanying drawing, which represents a side elevation 10 of a bulb embodying my new design.

The design in its entirety shows a bulb having a cylindrical shank *a*, an annular hood or flange formation *b* below the upper end of the shank, and having the top surface tapering upward toward the shank, and a bulbous formation *c* below the hood and within the outer edge thereof and joining the under surface of the hood on a line concentric with the exterior of the shank, the bulbous formation

for its major portion being approximately 20 cylindrical, the lower end of the bulb curving inward and terminating in a point. The portion *c*, except as to its point, simulates in general a teacup, and the hood *b* more or less 25 simulates a saucer. Further, part *c* is shown ornamented by intersecting lines forming facets.

The leading feature of my design consists in the bulbous formation at the bottom and the hood-like formation thereabove.

I claim—

The design for an incandescent-lamp bulb, substantially as herein shown and described.

LAWRENCE H. DOLAN.
